UNITED STATES PATENT OFFICE.

JAMES S. LANG, OF BOSTON, MASSACHUSETTS.

PROCESS FOR REMOVING SNOW OR ICE.

No. 863,856.

Specification of Letters Patent.

Patented Aug. 20, 1907.

Application filed March 16, 1907. Serial No. 362,722.

To all whom it may concern.

Be it known that I, JAMES S. LANG, of Boston, in the county of Suffolk and State of Massachusetts, a citizen of the United States, have invented a new and useful Improvement in Processes for Removing Snow or Ice, of which the following is a full, clear, and exact description, reference being had to the accompanying drawings, forming a part of this specification, in explaining its nature.

10 My invention relates to an improvement in that process of removing snow or ice which consists in distributing on the snow or ice an inflammable volatile liquid and igniting the vapor of such liquid.

The ordinary method of practicing this process has 15 been to first pour or sprinkle the inflammable liquid upon the snow or ice and afterwards to ignite the vapor of such liquid by applying a flame to it. The process as thus practiced, though of great utility, is not only a slow one involving distinct steps, but it 20 is also an uneconomical one for the reason that before the vapor of the liquid can be ignited after it has been poured out or distributed, a considerable amount of the vapor has already escaped and the benefit derived from its ignition become lost.

25 The present process consists in igniting the vapor arising from the liquid poured upon the snow or ice at the same time that it is being poured out by means of a flame produced from the ignition of the vapor arising from the stream of volatile liquid during the application thereof to the snow or ice. By this is meant that a small portion only of the inflammable liquid will have become reduced to vapor before the remainder of the liquid has become deposited upon the snow or ice upon or over which it has been poured. Inasmuch as vapor is constantly arising from the liquid stream during the act of pouring out the liquid, this 30 course becomes ignited by the primary ignition of the vapor providing a flame reaching to the snow

or ice on which the liquid is poured and continuing as long as the liquid is being poured out. Such a continuous flame of course acts to ignite the vapor arising from the liquid which has reached the snow or ice on or over which it has been poured and eliminates the necessity of any further ignition.

The primary ignition of the vapor may be successfully accomplished by applying a burning taper to the stream of liquid as it is poured out whereby the vapor arising therefrom will be ignited. Such vapor may also be ignited by means of a torch maintained in a position closely adjacent to the pouring stream 50 of liquid or in any other way agreeable to the operator.

With such mode of application one can cover a great amount of surface in a very short time and practically none of the vapor becomes lost, for at the same time the liquid is being applied to the snow or ice 55 the vapor arising from it has become ignited by reason of the primary ignition.

My improved process for removing snow or ice accordingly consists in first igniting the vapor of a volatile inflammable liquid and then applying such liquid 60 with the vapor thereof burning to the snow or ice.

Having thus fully described my invention, I claim and desire to secure by Letters Patent of the United States:—

1. The process of removing snow or ice consisting in 65 igniting the vapor of a volatile inflammable liquid and then applying such liquid with the vapor thereof burning to the snow or ice.

2. The process of removing snow or ice consisting in pouring upon the snow or ice an inflammable volatile 70 liquid and igniting the vapor arising therefrom by a flame produced by the ignition of vapor rising from a stream of the volatile liquid during the application thereof to the snow or ice.

JAMES S. LANG.
